UNITED STATES PATENT OFFICE.

JOHN A. HOLMQUIST, OF WOODLAWN, PENNSYLVANIA.

CRIMPING-DRUM FOR WIRE-FENCE MACHINES.

1,378,957.

Specification of Letters Patent.

Patented May 24, 1921.

Application filed March 22, 1920. Serial No. 367,706.

To all whom it may concern:

Be it known that I, JOHN A. HOLMQUIST, residing at Woodlawn, in the county of Beaver and State of Pennsylvania, a citizen 5 of the United States, have invented or discovered certain new and useful Improvements in Crimping-Drums for Wire-Fence Machines, of which improvements the following is a specification.

10 My invention relates to wire-fence machinery, and concerns the particular construction of the crimping drum, an essential feature of commercial machines of the present day.

15 The wire fence or field fence of frequent use, made in continuous length, consists of a plurality of parallel strand wires, interconnected by stay wires which bridge at intervals the spaces between the strand wires; 20 the fence, then, is characterized by having longitudinally extending rectangular meshes. A further feature is that the strand wires are, at regularly recurrent intervals, and in the spaces between the points where the stay 25 wires are applied, crimped into short waves of relatively short radius. These crimps are formed for two purposes: first, to take up small irregularities in manufacture; and second, to render the fence slightly expensi- 30 ble and contractible without lateral distortion when being installed and when in service.

I shall illustrate my invention as applied in a machine of the Denning type (see 35 the Denning Patent No. 816,538), but it will be understood that it is not necessarily so limited, being applicable generally to any fence machine in which crimping is to be effected. In the Denning machine, and in 40 machines of certain other types as well, the crimping drum serves, not merely to put the crimp in the strand wires of the otherwise completed fence, but also as the instrumentality by which tension is exerted on the 45 strand wires, to draw them through the machine. This feature last named is present in the crimping drum chosen for purposes of illustration, but it will be understood that it is not essential to my present invention.

50 In the accompanying drawings, Figure I is a view in side elevation of a machine of the Denning type, to the crimping cylinder of which my present invention is applied; Fig. II is a view to slightly larger scale trans- 55 versely through the crimping drum, dissected

from the remainder of the machine. In this Fig. II parts are broken away to show, in elevation, the cylinder head. Fig. III is a view in medial longitudinal section of the crimping drum and showing also certain immediately associated parts. Fig. IV shows in plan, in section, and fragmentarily in side elevation, a certain cam track; and Fig. V shows in plan and elevation a second cam track. These are parts of the machine, and 60 their place and function will presently be described.

In the crimping drums of the typical Denning machine, the principle of operation has been to grasp the strand wires at two 70 closely adjacent points; and, while the wires are held at those points against displacement, to impose on the short span of wire between a thrust in the plane of the general extent of the fence and in a direction transverse to 75 its length. This was the natural way to effect the crimp; natural, because of the necessity of keeping the fence as a whole in alignment, and natural, further, because it is the small portion of the metal forming the bend, 80 rather than the large mass of the remainder of the fence, which is turned aside. The structure for accomplishing this has included two parallel bars with aligned notches, 85 spaced apart sufficiently to allow the development of the crimp between, and crimp-developing fingers pivoted between, with means for swinging the fingers to shape the wire into crimps.

In such an operation as fence-making 90 there are incidental minor variants: such, for instance, as irregularities in physical condition of material, the degree of wear of the machine parts, the effect of unworn replacements. As a result, minor irregularities are 95 found in the product. A machine may be set up and adjusted, to produce fence having an interval of say eight inches between adjacent stay wires; but it will be found by actual measurement of the fabricated article that there will in a length of fence produced be appreciable departures in dimension from that standard eight-inch space. Furthermore, the coils formed by the ends of the stay wires wrapped about the 100 strand wires are approximately an inch long, so that the length of free wire between adjacent stays is seven inches, more or less. It is within that seven inches that the crimping device must work. In machine building 105 110

it is found convenient to mount the crimping instrumentalities two by two on bifurcated supports, and to form the crimps in the strand wire closely adjacent and on either side of every second stay-wire coil, rather than at the mid point of the spaces between the coils. With the crimps so placed, the stay wire applied between is more effectually secured against displacement longitudinally of the strand wires.

The instrumentality which holds one portion of the wire against displacement while the crimp is being formed is, as has been indicated, a beam extending across the drum from head to head and sustaining the thrust of crimping, while the instrumentality which bends the wire is a finger, merely, pivoted to the beam. If then the main part of the web of fence be held stationary while the small length of wire which forms the crimp be bent aside, there will need to be two beams for each crimp, and a finger pivoted between. And if the bending instrumentalities are arranged in pairs to operate on either side of and closely adjacent to a stay-wire coil, the grouping of four beams becomes a matter of some difficulty, particularly in view of the fact that the space between each pair must be sufficiently wide to receive the stay-wire coil, with allowance for irregularity of the nature indicated.

In my crimping drum, I so far depart from the typical Denning arrangement, that it is the mid point of the crimp which I grasp and hold against displacement, and it is the remaining portion of the web of fence which I move forcibly to one side. The extent of this lateral displacement is so small that there is no consequent disturbance of the associated fence-forming operations, while the gain (and herein is the spring of my invention) lies in this: I need employ only one beam, in place of the two used by Denning, and so can build a drum on which the web of fence is less likely to foul. This reversal of parts and of movements is of particular advantage when it comes to the building of a drum with crimping instrumentalities grouped in pairs, to act upon the strand wires on either side of and closely adjacent the stay-wire coils.

Referring to the drawings, the crimping drum 2 is in Fig. I shown in its position in the machine. Comparing Figs. II and III the drum will be seen to consist of heads 40 and beams 41, mounted on a shaft 42. The drum may intermediate its length be strengthened by webs 43.

The beams 41 are arranged, it will be observed, in parallel pairs, the beams of each pair lying parallel one to another; and the spaces between the members of each pair conveniently narrower than the spaces between pairs. This space between the members of

each pair is designed to receive a stay-wire coil, and is conveniently made as small as may be, taking into account the irregularities described above in the spacing of the succession of the coils. The spacing is such that, when the parts of the machine are co-ordinated and operation is in progress, every second stay-wire coil along each strand wire will fall between the beams 41 forming a pair.

Each beam is notched with a succession of notches 44, spaced according to the spacing of the strand wires in the web of fence, and to each pair of beams is pivoted adjacent the notches a succession of doubly bifurcated crimping members 45. The fingers of the crimping members extend in pairs, closely overlying each beam 41 on either side. The arrangement is clearly shown in Fig. II.

Means are provided to impart to the crimping members a periodic swing across the notches and then back to retracted position; that is, from the position shown in the lower part of Fig. III to that shown in the upper part, and then back again. Such means are found in the push bars 46, which engage the inner ends of the clamping members and which move longitudinally to effect the end indicated. Movement of the push bars 46 to and fro, longitudinally of the crimping drum is effected periodically in the course of rotation by means of cams 47, 48. These two cams, shown in assembly in Fig. III, are shown in detail in Figs. IV and V. It will be understood that they are carried rigidly in the machine frame, and are so arranged that each completes the circle partly described by the other. In other words, arranged at opposite ends of the drum, they act in alternation.

The operation will readily be understood. The drum is arranged to receive a web of fence upon its lower face, to crimp the web as it rises, and to release the crimped web from its upper face. Fig. III shows the drum with the clamping members 45 below held in retracted position by engagement of beam 46 with cam 48, and notches 44 in beam 41 open. When these parts are in this position the web of fence comes to position in the notches. Continued turning of the drum brings the beam 46 beyond the end of cam 48 and into contact at its opposite end with cam 47. By such engagement and consequent thrust, beam 46 is swung to the right until it comes to the position shown in the upper part of Fig. III. In consequence, the whole web of fence is pushed to the left, except only the lengths of wire resting in notches 44, and so the crimps are formed. Fig. III shows the upper beam 46 about to pass beyond the end of cam 47. Immediately that happens, the fingers 45 are free to swing; and, the now finished fence being

at this point lifted, the strand wires rise from the notches 44, swinging the clamping members aside as they escape. The aid of cam 48 may of course be had to open the 5 clamps allowing the fence to escape.

The advantage of this arrangement over the pre-existing one, in which two beams and one finger perform the office here performed by one beam and two fingers, has 10 been sufficiently indicated.

In the ensuing claims I define what is of the essence of my invention; otherwise, the mechanism is susceptible to modification, my showing being in these respects exemplary 15 merely.

I claim as my invention:

1. In a wire-fence machine, a rotary crimping drum including a pair of beams extending longitudinally of the drum and 20 arranged in parallelism, and provided with a succession of alined notches, and a corresponding succession of doubly bifurcated crimping members pivoted to said beams adjacent said notches with fingers overlying 25 each of said beams on either side, and means for swinging said crimping members in pre-

determined synchronism with the rotation of said drum, substantially as described.

2. In a wire-fence machine, a rotary crimping drum, its cylindrical face formed 30 of a succession of pairs of parallel beams, the beams provided with a succession of alined notches, each pair of beams provided with a corresponding succession of doubly bifurcated crimping members pivoted to 35 said beams and having fingers overlying each beam on either side and in the range of pivotal swing of the members movable across said notches, a thrust beam engaging the succession of crimping members pivoted 40 to each pair of parallel beams, and means for driving each thrust beam longitudinally of the drum as in the rotation of the drum it comes to a certain point in its path, substantially as described. 45

In testimony whereof I have hereunto set my hand.

JOHN A. HOLMQUIST.
